UNITED STATES PATENT OFFICE.

HARRY H. PEMBERTON AND CHARLES A. MOORE, OF ROSEVILLE, OHIO.

PHONOGRAPH-RECORD CABINET.

1,264,851.

Specification of Letters Patent.

Patented Apr. 30, 1918.

Application filed May 17, 1916. Serial No. 98,084.

To all whom it may concern:

Be it known that we, HARRY H. PEMBERTON and CHARLES A. MOORE, citizens of the United States, residing at Roseville, in the 5 county of Muskingum, State of Ohio, have invented a new and useful Phonograph-Record Cabinet; and we do hereby declare the following to be a full, clear, and exact description of the invention, such as will enable others skilled in the art to which it 10 pertains to make and use the same.

This invention relates to the art of cabinets, and more particularly to a cabinet for talking machine records, disk records that 15 are used upon victrolas and grafonolas and similar machines.

One of the objects of the invention is to provide a cabinet having a plurality of compartments to hold the disk records, there being 20 a plurality of pull rods mounted in guides of the cabinet and provided with downwardly extending arms, disposed in the rear of the edges of said records, whereby upon pulling any one of the rods, the record 25 (which may be listed corresponding to the number of the rod) will be discharged from its respective compartment. A list of records numbered according to the numerals 30 upon the pull buttons of the rods may be carried by the inner face of the door of the cabinet.

In practical fields the details of construction may necessitate alterations falling within the scope of what is claimed.

35 The invention comprises further features and combination of parts as hereinafter set forth, shown in the drawings and claimed.

In the drawings,

Figure 1 is a view in perspective of the 40 improved record cabinet constructed in accordance with the invention.

Fig. 2 is a vertical sectional view on line 2-2 of Fig. 1.

Fig. 3 is a vertical sectional view on line 45 3-3 of Fig. 1 at right angles to Fig. 2.

Fig. 4 is a detail perspective view of one of the pull rods.

Referring more especially to the drawings 50 1 designates a cabinet, preferably rectangular in contour, which is provided with a bottom 2 and a horizontal partition 3 spaced considerably above the bottom. This partition 3 is connected to the opposite sides of the cabinet in any suitable manner, but is 55 somewhat shorter than the depth of the cabinet, thereby forming spaces 4 and 5 for-

wardly and rearwardly. The under face of the partition 3 is provided with a plurality of grooves 6 arranged in parallelism with each other and at spaced intervals. The upper face 7 of the bottom 2 is slightly upwardly inclined toward the forward portion of the cabinet to the point as indicated at a, beyond which the bottom is inclined forwardly and upwardly at a greater angle 65 than the first inclined portion, so as to act as a stop for the record, as it is rolled out on its edge. The bottom 2 is provided with a plurality of grooves 8 arranged in parallelism, and at spaced intervals corresponding 70 to the spaced intervals of the grooves 6. Secured in the grooves 6 and 8 are the upper and lower edges of a plurality of vertical partitions 9, forming compartments for disk records 10. Rising upwardly from the forward and rear portions of the horizontal partition 3 are partition walls 11 and 12 having a plurality of axially aligned apertures or openings 13 and 14. Arranged in said guide openings or apertures 13 and 14 is a 75 plurality of pull rods 15 having their forward ends provided with knobs or buttons 16, and their rear portions terminating in downwardly extending arms 17 having flattened portions 18, which fit edge-wise in the 80 rear of the record compartment, so that the rear edges of the records will contact with the front faces of said flattened portions, whereby when any one of said rods is pulled, its respective arm 17 will discharge or move 85 a record until the inclined part 19 of the bottom will limit the record in its movement. The knobs or buttons 16 are so spaced from the bend where the arms 17 depend from the body of the rods 15, that when said 90 rods are pushed back in place, the arms 17 are held spaced from the back of the cabinet whereby as the records are inserted in their compartments the arms 17 will cushion the records, thereby relieving the sudden jar on 95 the records. A record having been pushed forwardly to be limited by the inclined surface 19 it may be easily grasped and removed from its compartment. As shown there are fifteen compartments, therefor the 100 knobs or buttons are numbered accordingly (1 to 15 inclusive), and arranged on the inner face of the front closure 21 is a chart 22 having a plurality of lines 23 numbered (1 to 15 inclusive) corresponding to the 105 knobs or buttons. The titles of the records are written upon the lines 23, and the records 110

are placed in the compartments 24, so that their titles would correspond to the numbers adjacent the lines 23 and numbers on the buttons or knobs. Therefore, should the record entitled "Ben Bolt" (which is written on the first line of the chart) be desired, the operator pulls the button numbered 1, in which case the downwardly extending arm 17 of said pull rod will discharge the record "Ben Bolt" from its respective compartment, until it is limited by the inclined surface 19, thereby enabling the record to be grasped by the hand of the operator. Each of the other records that may be in the compartments may be removed in a like manner. The rear of the cabinet is provided with a hinge closure 26, which may be opened should any of the pull rods and their arms need repairs.

20 The invention having been set forth, what is claimed as new and useful is:—

In combination with a disk record cabinet, the top of which has a depending part spaced

between the front and rear walls of the cabinet, said depending part having oppositely arranged alined guides, a plurality of record ejectors, each ejector comprising right angle extending arms, one extending horizontally and mounted in a pair of said directly opposite guides, the other arm depending downwardly and being resilient, and means on the end of the horizontal arm adapted to engage the front of said depending part so as to hold the depending arm spaced from the back of the cabinet for cushioning the record as it reaches its normal position in its compartment of the cabinet.

In testimony whereof we have signed our names to this specification in the presence of two subscribing witnesses.

HARRY H. PEMBERTON.
CHARLES A. MOORE.
